UNITED STATES PATENT OFFICE.

JUDAH LEONARD GEHORSAM, OF NEW YORK, N. Y.

MOUTH-PROP.

No. 888,484.

Specification of Letters Patent.

Patented May 26, 1908.

Application filed February 5, 1908. Serial No. 414,291.

To all whom it may concern:

Be it known that I, JUDAH LEONARD GEHORSAM, a citizen of the United States, residing in borough of Brooklyn, city of New York, in the county of Kings and State of New York, have invented certain new and useful Improvements in Mouth-Props, of which the following is a specification.

This invention relates to a prop or instrument for holding open the mouth of a patient during a surgical operation performed in the mouth or throat.

In using mouth or jaw props as heretofore constructed, it often happens that after the patient's mouth is opened and the prop is fixed in position, the patient's mouth will yield still farther, and in consequence, the prop will loosen and dangle about, thus proving a serious annoyance and even a source of danger where a delicate operation is being performed, for instance in the throat of the patient.

One of the principal objects of my invention is to overcome this difficulty, and to this end I have constructed a jaw prop which will automatically open itself to follow the movement of the patient's jaws during the further relaxation thereof as the operation within the mouth progresses; so that there is no danger of the prop becoming loose and swinging about and distracting the surgeon. I further provide means for automatically locking the jaws of the instrument at any point to which they may open themselves under the circumstances recited.

The means for causing the jaws to be self-opening may be in the form of a spring coiled around the pivot of the jaws of the instrument and extending along the jaws to bear thereon and tensioned to separate them. I further provide means for locking the jaws normally closed, so that they may be conveniently manipulated while introducing them between the jaws of the patient, this locking means being however releasable at the will of the surgeon.

Upon the tips of the jaws of the instrument, I provide pads to engage the teeth of the patient, said pads preferably in the form of lead or other soft disks swiveled upon the tips of the instrument, so as to permit the latter to be swung to one side after it has been opened between the jaws of the patient, the swiveling of the pads insuring the teeth against injury while the instrument is being

swung to one side. When the instrument is closed, the pads preferably are inclined to each other to form a wedge-like arrangement for convenience in introducing between the patient's jaws.

In the accompanying drawings, Figure 1 is a perspective view of a surgical jaw prop constructed in accordance with my improvements and partly open. Fig. 2 is a longitudinal sectional view of the instrument, which is illustrated as holding the patient's jaws open, and also as swung to one side to be out of the way of the surgeon. Fig. 3 is a plan showing the instrument in place in the mouth of the patient, only the lower jaw of the patient being illustrated. The dotted lines show how the instrument may be swung to one side after the jaws of the patient have been opened thereby. Fig. 4 illustrates the manner of introducing the tip of the instrument between the jaws of the patient.

The mouth prop comprises jaws 1, 2 pivoted together at 3 and having handles 4, 5, which are pressed together to open the jaws 1, 2. The latter are formed with flattened tips 6, 7, upon which are swiveled lead or other tooth pads 8, 9 by means of pins or pivots 10 or in any suitable manner. When the instrument is closed, the pads 8, 9 are inclined towards each other to form a wedge-like construction for convenience in insertion between the upper and lower teeth of the patient, Fig. 4.

After the insertion of the instrument, the handles 4, 5 are forced towards each other to open the jaws of the patient. This operation is conveniently performed with the instrument in a position shown in full lines in the plan at Fig. 3; and then the instrument is swung around to the dotted line position where it is out of the way of the surgeon. The jaws 1 and 2 are bowed to leave a large opening to give access to the patient's mouth as at Fig. 2. If the patient's jaws should further relax, a spring 11, coiled about the pivot 3 of the instrument and having ends 12, 13 lying within the hollow jaws 1 and 2, and tensioned to press the latter apart, will cause the jaws to open automatically to follow the excessive opening movement of the patient's jaws, so that the instrument does not become loose.

A ratchet 14 is pivoted at 15 to the handle 5 and provided with fine teeth 16 to engage the edge 17 of a hole 18 in the handle 4, the

- ratchet projecting through said hole and being pulled by a spring 19 to cause the teeth 16 to engage said edge 17. The function of the ratchet is to lock the jaws 1, 2 open at 5 any position to which they may be set by either the handles 4, 5 or the spring 11. It will be seen that the jaws 1, 2 are self-opening by reason of the spring 11 and self-locking by reason of the ratchet 14 and spring 19.
- 10 I provide also for locking the jaws 1, 2 closed in the Fig. 4 position, this being accomplished by means of a jog or tooth 20 formed upon the end of the ratchet 14, to catch on the inner side of the edge 17 when the handles 4, 5 are 15 pulled wide apart, thereby locking the handles in that position, and the jaws in the Fig. 4 position, as will be understood. A finger-piece 21 formed upon the end of the ratchet wheel may be pulled back by the surgeon 20 after the introduction of the instrument, as at Fig. 4, thereby releasing the handles 4, 5 to permit them to be pressed towards each other.

Variations may be resorted to within the 25 scope of the invention, and portions of the improvements may be used without others.

Having thus described my invention, I claim:

1. A mouth prop comprising a pair of jaws, 30 a pair of handles connected thereto, a spring tensioned to open said jaws to follow the involuntary opening of the mouth of the patient, and means to automatically lock the jaws open at any position to which they are 35 moved by said spring.
2. A mouth prop comprising a pair of jaws, a pair of handles connected thereto, a spring tensioned to open said jaws to follow the involuntary opening of the mouth of the patient, and a fine-toothed spring-pressed 40 ratchet connected to the jaws to hold them open.
3. A mouth prop comprising a pair of jaws, a pair of handles connected thereto, a spring 45 tensioned to open said jaws to follow the involuntary opening of the mouth of the patient, and releasable means to lock the jaws in closed position.
4. A mouth prop comprising a pair of jaws, 50 a pair of handles connected thereto, a spring tensioned to open said jaws to follow the involuntary opening of the mouth of the patient, and a fine-toothed spring-pressed ratchet connected to the jaws to hold them 55 open, said ratchet also provided with a tooth

to hold the jaws closed, and a finger piece to release the jaws.

5. A mouth prop comprising a pair of jaws, a pair of handles connected thereto, a spring tensioned to open said jaws to follow the involuntary opening of the mouth of the patient, a spring tooth to hold the jaws closed, and a finger-piece to release the jaws. 60

6. A mouth prop comprising a pair of jaws, a pair of handles connected thereto, a spring 65 tensioned to open said jaws to follow the involuntary opening of the mouth of the patient, means to lock the jaws in closed position, and a finger-piece to release the jaws.

7. A mouth prop comprising a pair of self-opening and self-locking jaws having portions 70 to engage the upper and lower teeth or jaws of the patient.

8. A mouth prop comprising a pair of self-opening and self-locking jaws having portions 75 to engage the upper and lower teeth or jaws of the patient; releasable means being also provided to lock the jaws of the instrument together for insertion into the mouth of the patient. 80

9. A mouth prop comprising a pair of jaws each having a tooth-pad swiveled thereon to admit of the instrument being swung to one side while it holds open the jaws of the patient; said tooth-pads in the form of disks 85 pivoted upon flat tips formed upon the jaws and arranged face to face, and a spring tensioned to open said jaws to follow the involuntary opening of the mouth of the patient.

10. A mouth prop comprising a pair of 90 jaws each having a tooth-pad swiveled thereon to admit of the instrument being swung to one side while it holds open the jaws of the patient; said tooth-pads in the form of disks 95 pivoted upon flat tips formed upon the jaws and arranged face to face, and a spring tensioned to open said jaws to follow the involuntary opening of the mouth of the patient, and means to automatically lock the jaws of the instrument open at any position to 100 which they are moved by said spring.

11. A mouth prop comprising a pair of self-opening and self-locking jaws having swiveled pads to engage the upper and lower teeth or jaws of the patient.
